Application June 29, 1935, Serial No. 29,112

8 Claims. (Cl. 198—128)

The invention relates to building concrete structures such as tunnels, sewers, conduits, and the like.

One object of the invention is to provide apparatus for centrifugally slinging concrete to pack it into place in building concrete tunnels, conduits, and the like. By centrifugally slinging the concrete into place it has been found that the concrete becomes properly packed to eliminate undesirable voids and particularly in the side and cap portions of a tunnel or conduit.

Another object of the invention is to provide apparatus for centrifugally slinging concrete in building concrete structures.

Another object of the invention is to provide a centrifugal slinger for the construction of concrete tunnels or conduits, which is equipped for changes of position to sling concrete laterally to either side or in the cap portion.

Another object is to provide a centrifugal concrete-slinger which is equipped for projecting concrete at different angles.

Another object of the invention is to provide a concrete slinger which is efficient in operation and has a large capacity.

Other objects will appear from the detailed description.

The invention consists in the several novel features which are hereinafter set forth and are more particularly defined by claims at the conclusion hereof.

In the drawings:

Figs. 1 and 2 are cross-sections of a tunnel illustrating the method of slinging concrete to build up the side-walls of the tunnel.

Fig. 3 is a longitudinal section of the tunnel illustrating the method of slinging concrete to form the cap or key-section;

Fig. 4 is a transverse section of the centrifugal slinger;

Fig. 5 is a section on line 5—5 of Fig. 4;

Fig. 6 is a plan of the slinger;

Fig. 7 is a detail side elevation of one of the devices for adjusting the casing to keep taut the chain for driving the rotor of the projector;

Fig. 8 is a detail showing one of the paddles on the rotor of the slinger;

Fig. 9 is a detail section through one of the paddles;

Fig. 10 is a transverse section of a modified form of the invention; and

Fig. 11 is a side elevation of the form of the invention illustrated in Fig. 8.

The centrifugal projector for slinging the concrete is exemplified with a drum or casing pro-

vided with an inlet for the concrete adjacent its lower portion, a rotor in the casing provided with paddles for centrifugally slinging the concrete through a peripheral outlet in the casing after it has travelled around the casing and been subjected to centrifugal force therein, and mechanism for driving the rotor at the proper speed to sling the concrete from a position inside of the tunnel into the form for the concrete. This apparatus is adapted to project the concrete tangentially and obliquely to fill the form at either side of the tunnel and is adjustable to vary the position of the discharge-opening so the paddles of the rotor will project the concrete at different angles, as the concrete is built up, and also into the cap portion or section of the lining.

The projector casing comprises a pair of circular sides 12, each formed of plate-metal fixedly secured by screw 13 to a hub 14, and having an outwardly extending circumferential flange 15, a peripheral wall 16 secured on the flanges 15 of the casing by clamping bands 17 which extend around the marginal portions of said wall and are provided with bolts 18 for firmly securing the bands around wall 16 to fixedly secure said wall to the sides 12 of the casing. On account of the wear to which the inner face of peripheral wall 16 is subjected it is preferably formed of a plate of metal bent into cylindrical shape and removably clamped to the side plates 12 so the wall can be conveniently replaced when it becomes worn. The ends of this cylindrical plate are spaced apart to leave a gap or peripheral opening 19 through which the concrete is projected from the casing. The sides 12 of the casing are held in a spaced relation independently of the peripheral wall plate 16 by spacer bolts 12^a which are fixed in brackets 12^b which are fixed to the outer faces of the casing sides. This construction exemplifies a casing having its peripheral wall formed of a cylindrical plate of metal which can be readily replaced when it becomes worn and can be produced at a low cost of manufacture.

Each side 12 of the casing is provided with an arcuate opening 20 through which the concrete is supplied to the lower portion of the drum. A hopper 64 is mounted adjacent each side of the projector casing to direct the concrete through the inlet openings 23 into the lower portion of the casing where it will be engaged into the path of the paddles. These hoppers are fixedly supported on the supporting frame members 32 by bars 65. In practice a substantially regular stream of concrete is delivered into either of the hoppers 64 while the projector is in operation.

This may be done by any suitable conveying apparatus, such as an endless belt or other suitable conveyor from the concrete mixer.

The hubs of the casing are rotatably mounted in hangers or brackets 30 which are carried by a supporting frame having its base extending under the casing and comprising upstanding sides or members 32 at the sides of the casing, angle cross beams 33 and a central transverse channel bar 34 all of which are rigidly secured together in any suitable manner. This supporting frame exemplifies a structure which is adapted to support the projector from below so as to leave clearance for the slinging of the concrete through the peripheral discharge opening in the casing within a sufficient range to permit the concrete to be projected laterally and downwardly or laterally and upwardly to sling the concrete over the top margin of the form as it is successively built up to higher levels for the sides of the tunnel.

The rotor for centrifugally projecting the concrete from the casing comprises a hub 21 keyed to a drive shaft 22 which is journaled in the hub 14 of the casing, a pair of oppositely extending radial arms 23, and paddles 24 carried at the outer ends of said arms. Each arm 23 is preferably formed of plate metal and has welded to its outer end a tangentially extending plate 25. Each paddle blade consists of a strip of rubber 26 which is backed on plate 25 and on its front has a face plate 27. The rubber strip and plate are removably secured to plate 25 by bolts 28. The outer and side margins of the rubber strip 26 are free to engage and wipe the contiguous surfaces of the casing. The front or operative face of each paddle 24 is tangential or oblique to its radius so that in its rotation the concrete will be directed toward the angular space adjacent the line of contact between the outer end of the rubber plate 26 and the inner surface of the peripheral wall 16 of the casing so that the concrete in transit from the lower portion of the casing to its upper portion will be packed before it is discharged through opening 19. It has been found that by providing the paddles with rubber blades for engaging the periphery and sides of the casing the liquid content of the concrete will be lifted in the casing with the solids and projected therefrom, so that the concrete projected will be evenly constituted. These strips, when made of rubber of the density of tire rubber, have been found to be durable.

A series of sector-shaped plates 29 are secured to the inner faces of the side plates 12 in the zone traversed by the elastic blades 26. The ends of said blades wipe the inner faces of plates 29 to prevent the escape of the concrete around the ends of the paddles while the concrete is being lifted in the casing and until it is discharged therefrom. The inlet openings 20 for the concrete are disposed in the lower arc of the casing and the discharge opening 19 is located in the upper portion of the casing so that each of the pair of paddles will, in its rotation, traverse the lower arc of the casing, engage a batch of concrete and confine it between the periphery and sides of the casing and lift the batch to the upper portion of the casing. During this movement the concrete will be subjected to centrifugal force and the batch will be packed. As each paddle reaches the discharge opening 19 the batch of concrete lifted by it will be projected by the paddle and centrifugal force from the casing. In practice a casing of ap-

proximately four feet in diameter with a rotor travelling at a speed ranging from 115 to 165 revolutions per minute will compact the concrete and project it through outlet 19 with such force that it can be controllably delivered or placed approximately eight to ten feet from the point of discharge from the casing.

The mechanism for driving the paddles comprises an electric motor 35 mounted on an end plate 36 which is fixed to the frame in which the projector is mounted, a pinion 37 on the motor-shaft, a gear 38 meshing with said pinion and fixed to a shaft 39 which is journaled in bearings 40, a sprocket wheel 41 fixed to one end of shaft 39, a chain 42 driven by said sprocket 15 and a sprocket wheel 43 fixed to the shaft 22 of the rotor and driven by chain 42. The brackets 30 which carry the shaft 22 of the rotor are connected to the supporting frame members 32 by bolts 60 which pass through slots 61 in said brackets to permit the casing and rotor to be adjusted as a unit relatively to the drive shaft 39 to keep the driving chain 42 taut. Rods 62 have their inner ends welded to brackets 30 and their outer ends provided with screw threads for nuts 63 which bear against the frame members 32 for convenience in adjusting said brackets. The base of the supporting frame for the projector is swiveled to turn horizontally to permit the projector to be rotated to sling the concrete 30 along the sides to either side and also to permit the projector to be turned so the paddles will rotate longitudinally of the tunnel or conduit in order to sling concrete into the cap section or portion thereof. For this purpose a vertical spindle 44 is fixed to and depends from the channel bar 34 of the projector supporting frame and journaled in a socket 45 on a wheeled truck which comprises a frame composed of channelled sills 46 rigidly connected by cross channel bars 47 and wheels 48 on axles 49 which are journaled in the truck frame and are adapted to run on rails 50 which are usually laid on a temporary platform or staging 51 in the tunnel or conduit. This mounting for the concrete-projector makes it possible to rotate it so that the discharge opening 19 for the concrete may be positioned to sling the concrete toward either side of the tunnel by swinging the projector approximately 180°, which movement will also cause the paddles 24 to project the concrete accordingly. It also permits the projector to be swung horizontally to sling the concrete along a side of the tunnel within a certain range.

In order to vary the angle at which the concrete is discharged to direct the stream tangentially and downwardly when building the lower portions of the sides of the tunnel and to direct it higher as the form is filled and built up, the casing is rotatable around the axis of the projector to bring the discharge opening 19 into position to sling the concrete at different vertical angles. For this purpose the hubs 14 of the casing are rotatable in brackets 30 and a windlass is provided for rotating the casing. This windlass comprises a hand wheel 52 fixed to a transverse shaft 53 which is mounted in bearings 54 fixed to the supporting frame for the projector and a cable 55 having its ends connected as at 56 and 57 to lugs fixed to the clamping bands 17. By rotating the hand wheel 52 in either direction the casing may be rotated to control the position of the discharge opening 19 and the angle at which the concrete will be discharged from the casing. A toothed wheel 58 75

on the shaft 53, and a dog 59 adapted to engage said wheel are adapted to lock the windlass and the casing in assigned positions.

The method of placing concrete in a tunnel or conduit and the operation of the slinging apparatus is as follows: After a section of the tunnel has been excavated in the usual manner as well understood in the art and circumferential ribs A with a sheathing B have been put in place to hold the surrounding material, the concrete for the base portion or floor C of the tunnel may be directly poured or spread into place in the usual manner. The side portions of the form are erected a few feet in height and the concrete 15 may be shoveled or poured directly into these lower side portions because these portions are readily accessible. When the form has been filled with concrete to approximately the top of the partial form, sections of several feet of form 20 are added at one side of the tunnel. The projector is then adjusted by means of the windlass to sling the concrete downwardly and laterally to that side of and lengthwise of the tunnel within range of the projector until the portion of 25 the form which has been erected has been filled. While this is done the form is built up at the opposite side of the tunnel. Next the projector will be swung horizontally about 180° to sling concrete into the form at the latter side of the 30 tunnel until it has been built up to the top of the incomplete form. During this filling the form will be again built up for several feet at the opposite side. The projector will be rotatably adjusted to sling concrete over the top of 35 the section of the form last erected and obliquely against the tunnel liner until the concrete reaches the level of the form as far as erected. These steps will be repeated until the key or cap section or zone is reached where it 40 is impossible to project the concrete vertically into place. During these steps the projector will be rotated on the truck and the casing will be rotatively adjusted so the paddles will sling the concrete in the desired directions. When the concrete has been extended to the cap or key 45 zone the projector is rotated on the truck about 90° to bring its axis transverse of the tunnel as illustrated in Fig. 3 and the casing is adjusted so the concrete will be projected obliquely upward. The form is then completed under the 50 cap section step by step, with a steel sheet several feet in width, and the projector is operated to sling the concrete longitudinally of the tunnel and upwardly into the cap or key zone until it has been completely packed and filled. These 55 sheets may be successively put in place, so that the spaces above them will be comparatively short and can be packed with concrete without voids above them. By this method the cap or key zone of the concrete can be filled by projection so that it will be as solid as desired. This 60 is an important factor in the cap or key zone of the tunnel. When a longitudinal section of the tunnel has been completed in this manner, the projector will be moved to the next section and 65 these operations will be repeated.

In the modified form of the invention illustrated in Figs. 10 and 11 the rotor is reversible and is provided with oppositely facing, relatively 70 inclined, paddles 24^a, and the motor 35^a is of the reversible type. The casing is similar in construction to that previously described. The range of rotative adjustment of the casing is increased so that the peripheral discharge opening 19^a can be shifted to sling concrete to either

side of the tunnel and at different angles while filling the forms as before described. By operating the windlass for cable 54^a in this form of the invention the casing can be adjusted to vary the direction of the concrete for these purposes. 5 The driving mechanism for the projector is mounted on one side of the supporting frame to leave clearance for the projection of the concrete to either side of the tunnel. In this form 10 of the invention the projector and its supporting frame are mounted on the truck so it can swing 90° for filling the cap or key zone with concrete as previously described and to sling the concrete along the section within range of the projector.

The driving mechanism for the projector comprises an electric motor 35^a, a bevel pinion 37^a on the motor shaft, a bevel gear 38 rotating on a stud 39^a, carried by the supporting frame, a sprocket 41^a fixed to rotate with gear 38^a, a chain 42^a driven by a sprocket 41^a, and a sprocket wheel 20 43^a fixed to the shaft of the rotor. All of this mechanism is mounted at one side of the supporting frame to leave clearance for the projection of the concrete to either side.

In the operation of this form of the invention 25 the casing is rotatively adjusted by the windlass to bring the discharge opening 19^a to the side where the concrete is to be projected and the reversible motor is operated to cause the paddles to rotate and lift the concrete from the lower 30 portion of the casing upwardly around the opposite side thereof and to sling it through said opening. When the concrete is to be discharged at the other side of the tunnel the casing is rotatively adjusted accordingly and the direction of 35 rotation is reversed which will cause the oppositely facing paddles to lift batches of concrete and to sling it in the desired direction.

The invention exemplifies a method of, and apparatus for, expeditiously projecting concrete 40 to form the sides and top of a tunnel or conduit and has a great capacity. It also exemplifies one which can be quickly and conveniently set to project the concrete to different elevations for successively filling the successively erected sections of the form and which results in making the concrete of substantially uniform density 45 without weak spots and defects.

The invention is not to be understood as limited to the details set forth and may be modified 50 within the scope of the claims without departing from the spirit and scope of the invention.

Having thus described the invention, what I 55 claim as new and desire to secure by Letters Patent is:

1. In a concrete slinger, the combination of a supporting structure, a casing supported by the structure and comprising sides and a cylindrical peripheral wall having a discharge opening for concrete, a vertically-operating rotor in 60 the casing comprising a shaft extending transversely through the casing and a paddle for traversing the outer portion of the casing, and adapted to centrifugally sling concrete through the discharge opening, one of the sides having an arcuate and elongated inlet opening for concrete disposed radially outward of the shaft and to deliver concrete longitudinally into the lower part of the casing and into the path of the paddle, mechanism for driving the rotor, means for rotatably 65 adjusting the casing in the structure to project the concrete at different vertical angles, and stationary means for delivering the concrete to the arcuate inlet opening.

2. In a concrete slinger, the combination of 75

- a supporting structure, a casing supported by the structure and comprising sides and a cylindrical peripheral wall having a discharge opening for concrete, a vertically-operating rotor in the casing comprising a shaft extending transversely through the casing and a paddle for traversing the outer portion of the casing and adapted to centrifugally sling concrete through the discharge opening, one of the sides having
- 5 a inlet opening to deliver concrete longitudinally into the lower part of the casing and into the path of the paddle, mechanism for driving the rotor, and means for rotatably adjusting the casing in the structure to project the concrete
- 10 at different angles, comprising a cable around the casing and a windlass for the cable.
3. In a centrifugal slinger, the combination of a casing comprising sides and a cylindrical plate of metal forming the outer wall and terminating
- 20 to provide a peripheral discharge opening, clamping bands for removably securing the plate on the sides, a rotor in the casing provided with a paddle for lifting concrete and sling it through the opening, and mechanism for driving the rotor.
- 25 4. In a rotary concrete slinger, the combination of a casing provided with a peripheral discharge opening, a supporting structure for the casing, a rotor provided with a paddle comprising a strip formed of elastic material and a rigid backing
- 30 and facing for said strip, and mechanism for driving the rotor.
- 35 5. In a rotary concrete slinger, the combination of a casing provided with a peripheral discharge opening, a rotor in the casing provided with oppositely facing means for respectively lifting and projecting concrete in opposite directions, means for driving the rotor in either direction to correspondingly project the concrete, and means for variably positioning the discharge-opening so the concrete will be discharged to one side of the casing when the rotor is driven in one direction
- 40

and to the other side when it is driven in the opposite direction.

6. In a rotary concrete slinger, the combination of a casing provided with a peripheral discharge opening, a rotor in the casing provided with oppositely facing, relatively angled, faces for respectively lifting and projecting concrete in opposite directions, means for driving the rotor in either direction to correspondingly project the concrete, and means for variably positioning the discharge-opening so the concrete will be discharged to one side of the casing when the rotor is driven in one direction and to the other side when it is driven in the opposite direction.

7. In a rotary concrete slinger, the combination of a rotatably mounted casing provided with a peripheral discharge opening, a rotor in the casing provided with oppositely facing means for respectively lifting and sling concrete when the rotor is driven in opposite directions, means for driving the rotor in either direction to project the concrete, and means for rotatably adjusting the casing to variably position the discharge opening so the concrete will be discharged to one side when the rotor is driven in one direction and to the other side when it is driven in the opposite direction.

8. In a rotary concrete slinger, the combination of a casing provided with a peripheral discharge opening, a rotor mounted to rotate vertically in the casing and provided with oppositely facing paddles for respectively projecting concrete when the rotor is driven in opposite directions, means for driving the rotor in either direction to project the concrete, means for variably positioning the discharge opening so the concrete will be discharged to one side when the rotor is driven in one direction and to the other side when it is driven in the opposite direction, and a vertical pivotal support for the casing.

WALTER F. PIPER.
